DRAFT AND BUFFING GEAR

Roland J. Olander, Chicago, Ill., assignor to W. H. Miner, Inc., Chicago, Ill., a corporation of Delaware

Application May 13, 1935, Serial No. 21,130

3 Claims. (Cl. 213—9)

This invention relates to improvements in draft and buffing gears especially adapted for use in connection with mine cars.

One object of the invention is to provide a combined draft and buffing gear of high capacity, designed especially for use in connection with mine cars and arranged to be mounted as a unit on the end of the car.

Another object of the invention is to provide a mine car draft and buffing gear including shock absorbing springs, wherein the springs are arranged parallel or transversely to the end of the car, thereby making it possible to utilize springs of relatively large size of high capacity.

A further object of the invention is to provide in a mechanism of the character specified in the preceding paragraph, frictional resistance means in connection with the cushioning springs, thereby obtaining exceptionally high shock absorbing capacity.

A more specific object of the invention is to provide a combined spring and friction shock absorbing mechanism for mine car gears, wherein the friction is produced by cooperating spring resisted friction wedge blocks, actuated in both buff and draft, so arranged that the springs extend transversely of the car, thereby making it possible to employ relatively large springs of high capacity.

Other objects of the invention will more clearly appear from the description and claims hereinafter following.

In the drawing forming a part of this specification, Figure 1 is a broken end view of a car illustrating my improved draft and buffing gear in connection therewith, the gear being shown in part elevation and part vertical section, the section corresponding substantially to the line 1—1 of Figure 2. Figure 2 is a part top plan and part horizontal sectional view, the section thereof corresponding substantially to the line 2—2 of Figure 3. Figures 3 and 4 are vertical sectional views, corresponding respectively to the lines 3—3 and 4—4 of Figure 2.

In said drawing, my improved mechanism is shown as combined with the end sill casting 10 of a mine car. Although the device is disclosed as combined with the end sill, it will be understood that the same may be made in the manner of a separate unit attached to the end sill or other end structure of the car.

My improved mechanism comprises broadly a supporting member A, which in this case is a part of the end sill 10; a buffing cap B; a wedge

block C; a pair of wedge shoes D—D; spring members E—E; and a draft or coupling pin F.

The supporting member A comprises the vertical back wall formed by the web of the end sill structure 10 of the car, a horizontally extending bottom wall section 11, vertical side wall sections 12—12, and a depending supporting fulcrum section 13, all formed integral with the end sill structure. The side wall sections 12—12 have inturned, vertically disposed, flanges 14—14, which cooperate with the buffing head or cap B to limit outward movement of the latter, as hereinafter more fully pointed out. The fulcrum section 13 comprises spaced side walls 15—15 and a curved bottom wall 16 providing the fulcrum seat. As will be evident upon reference to Figures 1 and 2, the bottom wall 11 of the supporting member A is open at said fulcrum section 13.

The buffing head or cap B is in the form of a hollow casting having spaced horizontal top and bottom walls 17—17, spaced vertical side walls 18—18, and a transverse vertical front wall 19. The outer face of the front wall 19 presents a buffing surface adapted to cooperate with a similar buffing member of an adjacent car. At opposite sides, at the rear end thereof, the buffing head B is provided with laterally extending retaining flanges 20—20 which are engaged in back of the flanges 14—14 of the supporting member A to anchor the buffing head to the support and limit outward movement of said head. As shown most clearly in Figures 2, 3, and 4, the inner end of the buffing head is normally spaced from the vertical back wall of the housing to provide for the necessary inward movement of the head during a buffing action. In assembling the buffing head B with the supporting member A, the same is engaged between the walls 12—12 and in back of the flanges 14—14 of said walls by sliding the head downwardly between said walls. The bottom wall 17 of the buffing head B is centrally cut away, as indicated at 21, to accommodate the bottom portion of the wedge block C and the lower end of the coupling pin F. The top wall 17 of the buffing cap B is provided with an opening 22 through which the coupling pin F extends, said opening being of sufficient length to permit the necessary movement of the pin F during draft action of the gear.

The wedge block C which, in effect, forms the draft member of the gear, is in the form of a rocker having a downward extension 23, which is rounded and bears on the fulcrum section 13 of the supporting member A. The block C has a

flat vertical rear face 24, which normally bears on the rear wall of the support A. The block C is forwardly tapered, as most clearly shown in Figure 2, and has a pair of vertical wedge faces 5 25-25 at opposite sides of the front end thereof. The wedge faces 25-25 are preferably slightly rounded so as to properly engage with the wedge faces of the shoes D-D when the wedge block C is swung outwardly during draft action of the 10 gear. The block C is further provided with a vertical opening 26 therethrough, adapted to receive the shank of the coupling pin F. Adjacent to the upper end of said opening 26, the block C is provided with a seat 27 adapted to 15 cooperate with shouldered means on the pin F to prevent downward movement of said pin in the block C.

The wedge shoes D-D, which are arranged at opposite sides of the wedge block C, have 20 wedge faces 28-28 on the inner sides thereof which cooperate with the wedge faces 25-25 of the block C. As shown in Figures 1 and 2 of the drawing, the wedge faces 28-28 are slightly rounded. At the forward end, each shoe is provided with a substantially flat, transverse friction surface 29, which bears on the inner surface of the front wall 19 of the buffering head E. Rearwardly of the friction surface 29, each shoe is cut away at the outer side, as indicated at 30, 30 to provide a spring seat for the corresponding end of one of the spring members E.

The spring members E-E are disposed within the buffering cap or head E and are arranged transversely thereof, as clearly shown in Figures 1 and 35 2. Each spring member E preferably comprises inner and outer coils having their opposite ends bearing respectively on the spring seat 30 of one of the shoes D and the inner side of the corresponding side wall 18 of the cap or head E.

40 The coupling pin F has a substantially cylindrical shank portion which is engaged through the opening 26 of the wedge block C. At the upper end, the pin F is provided with a rearwardly projecting head portion 31 which cooperates with the coupling link 32 to prevent accidental removal of said link. Below that portion of the pin F which extends through the coupling link 32, a forwardly extending lug 33 is provided on said pin which engages in the seat 27 of the block C, 45 thereby preventing downward displacement of said pin. In order to prevent the coupling pin F from being lifted out of the opening of the wedge block C, a locking member 34 in the form of a pin or rod extending through the lower end of 50 the shank of the pin F may be employed.

In the operation of my improved combined draft and buffering gear, when a buffering force is applied to the head E, the latter is moved inwardly, thereby carrying the wedge shoes D-D inwardly therewith. Inasmuch as the wedge C is held against rearward movement by engagement with the back wall of the support A, the shoes will be forced apart, due to the wedging action, and the springs E-E are compressed against the 60 side walls 18-19 of the cap or head E. This action continues until inward movement of the buffering head is arrested by engagement with the back wall of the support A. Inasmuch as the wedge face of the block C and the shoes D and 65 the friction surfaces of the shoes D and the friction surfaces of the buffering head E have sliding

movement on each other during the inward movement of the buffering head and spreading of the shoes D-D, the resistance of the springs is augmented by the frictional resistance between these members.

During a draft action, the pulling force applied to the coupling link 32 will be transmitted to the wedge C through the connecting coupling pin F, thereby swinging the wedge C forwardly and spreading the shoes D-D apart, thereby compressing the springs E-E. As will be evident, frictional resistance is thus produced between the wedge block C, the shoes D-D, and the friction surface of the buffering head B.

I have herein shown and described what I now consider the preferred manner of carrying out my invention, but the same is merely illustrative and I contemplate all changes and modifications that come within the scope of the claims appended hereto.

I claim:

1. In a combined draft and buffering gear for cars, the combination with an inwardly movable transversely elongated buffering cap at the end of the car and projecting outwardly beyond said end; of laterally acting spreading means, comprising an outwardly movable wedge block held against inward movement and a pair of wedge shoes cooperating with said wedge block, said shoes being movable inwardly with the buffering cap; a coupling pin engaged through said wedge block for connecting said block to a coupling link; means for limiting outward movement of the buffering head cap; and means within the buffering cap yieldingly resisting the spreading action of said spreading means.

2. In a combined draft and buffering gear for cars, the combination with an inwardly movable transversely elongated buffering cap at the end of the car and projecting outwardly beyond said end; of laterally acting spreading means including an outwardly movable wedge block and cooperating wedge shoes movable inwardly with the buffering cap; means for limiting inward movement of the wedge block; a coupling link; a coupling pin extending through said link and extending into and directly connected to said wedge block; means for limiting outward movement of the wedge shoes; and transversely disposed springs within the buffering cap yieldingly opposing spreading action of said spreading means.

3. In a combined draft and buffering gear for cars, the combination with an inwardly movable buffering head at the end of the car, said head having a transverse front wall and spaced side walls, 55 said front wall presenting a flat friction surface; of a pair of wedge shoes movable inwardly with said head said shoes being laterally slidably on the friction surface of said front wall; transversely arranged, elongated, helical spring members within the buffering head, each spring member being interposed between and bearing at opposite ends on said shoes and said side walls respectively and yieldingly opposing lateral separation of the shoes; an outwardly swingable 60 pivoted wedge member engaged between said shoes for forcing the shoes apart upon relative movement of the buffering head and wedge member; and means for swinging said wedge member outwardly away from the end of the car in draft. 65

ROLAND J. OLANDER.
